UNITED STATES PATENT OFFICE

LEON N. HAMPTON, OF NEW YORK, N. Y.

BOAT

Application filed December 15, 1930. Serial No. 502,322.

The present invention is directed to an improvement in manually propelled boats, and has for an objective a construction which is stable, requires no particular skill for operation, and in which power for operation is applied most efficiently.

As is well known oars, paddles and manually driven propellers are common means of boat propulsion. Oars and paddles are relatively efficient in skilled hands, but in the hands of the unskilled are beset with numerous annoyances such as splashing and dripping, a tendency to jump the oarlocks or slip overboard, and a general contrariness so far as maneuvering in close quarters and docking are concerned with attendant liability of damage and capsizing.

Propellers or screws overcome many of the difficulties above mentioned but here again the medium by which one's energy is transformed into power at the propeller must be given special consideration if any but very mediocre results are to be obtained.

As mentioned above, one of the objects of my invention is the provision of a construction in which this feature is given special consideration. In this connection it is to be noted that the racing shell is an example of a high standard of efficiency, but on the other hand the shell is only suitable for use by the skilled operator. I propose, however, to utilize in a propeller driven manually operated boat some of the features of the racing shell. In the shell the oarsman's seat is 35 slidable so as to enable him to adjust his body to the best position for the application of power to the oars. At the end of the power stroke the oarsman lifts the oars free of the water and quickly and with practically no effort slides back into position for the next stroke. In the construction of the present invention, although I provide a propeller driven boat instead of an oar driven, I have provided for movement of the operator so 45 that he may adjust his body to the most advantageous position, and may return to his original position with as little effort as does the oarsman in the shell.

Again in a propeller driven boat it is desirable for maximum results that the operat-

ing mechanism should be so constructed and arranged that the power of the legs, back and associated muscles as well as the muscles of the arms may be applied to advantage throughout a reasonably long movement, and that recovery from extended position to original position be speedy and effortless.

A further object of this invention, therefore, is the provision of a construction wherein not only is the operator's seat slidable, but the propelling mechanism is so constructed and so disposed with reference to the operator's seat as to enable the operator to apply his full effort thereto in the most efficient manner.

While the racing shell may represent a high standard of efficiency as to power application, it is recognized that it is unsuited for general use, in that it capsizes readily, skill is required in handling the oars, and it is not suited for transporting passengers or cargo. I propose to overcome this drawback, without sacrifice of the efficient application of power by providing two shell-like boats or pontoons arranged in spaced apart relation with a passenger and cargo cockpit suspended therebetween, the cockpit normally riding clear of the water. In addition the cockpit is arranged to mount the propeller, rudder mechanism and motor so that with careful attention to details a very efficient seaworthy and serviceable boat may be produced at low cost.

The shell-like boats or pontoons are sealed and hence cannot swamp and inasmuch as the buoyancy of the pontoons increases up to the point of submersion and remains undiminished even though submersion takes place, my enclosed shell or pontoon type of boat will strongly resist capsizing. Inasmuch as the construction of the present invention is such that the load is suspended between the pontoons in a cockpit lying close to the surface of the water my improved boat may be tipped at an angle far in excess of the capsizing angle of the conventional boat which of course adds materially to the boat's safety.

While a boat of the general construction or type of my boat is adapted to have its

propeller and rudder aft as in usual practice, the rudder and propeller may be mounted forward if desired. However, the present application will be directed mainly to a type of construction in which the rudder is mounted forward and the propeller aft, the mounting of the propeller forward and the rudder aft constituting the subject matter of another application.

- 10 I have already pointed out that I propose to mount the motor mechanism in such relation to the operator that the operator may apply power to the motor most efficiently. In this connection one embodiment of my invention which will be described in detail hereinafter provides a rack and pinion drive between the operator and the motor, a type of drive in which the direction of application of power does not change and is always in 15 the direction most useful in developing torque at the propeller.

It will be appreciated also from the description to follow that this type of drive is of such a nature that the drive is disengaged 20 on movement of the operator to starting position, thereby facilitating his return to such position and requiring effort on the part of the operator only in one direction of his movement. I also provide a clutch arrangement in connection with the motor in which 25 reversal of the direction of drive is made quietly and without any gear clashing, and in this same connection the rack is out of engagement with its cooperating pinion at 30 the time reversal is made so that the inertia of the moving parts is low. This, as will be 35 apparent, will facilitate reversal.

A further advantage of this type of drive resides in the fact that if desired the rack 40 may be resisted in its movement while engaged with the pinion should it be desired quickly to slow down the propeller.

The present invention also provides a construction in which a special coupling to be 45 described later is disposed between the motor shaft and the propeller shaft. The propeller shaft is carried in a pivoted torque arm. The pivot of this torque arm is on the parting center of the special coupling and should the propeller strike an obstruction the 50 torque arm will be raised to disengage the jaws of the coupling and hence disconnect the propeller from the motor. This provides a safety feature, the advantages of 55 which are obvious.

While the rudder of my improved construction may be mounted either forward or aft, I have shown the same mounted at the 60 forward part of the boat, permitting direct coupling between the rudder bar and the rudder, thereby eliminating the use of ropes, chains, pulleys, etc.

In the drawings accompanying this application:

Fig. 1 is an elevational view of a boat embodying my invention;

Fig. 2 is a plan view of the same;

Fig. 3 is a section on the line 3-3 of Fig. 1;

Fig. 4 is a longitudinal sectional elevational view of my improved boat showing one type of motor employed for driving the same;

Fig. 4a is a detail of clutch mechanism 75 shown in Fig. 4;

Fig. 5 is a section on the line 5-5 of Fig. 4;

Fig. 6 is a view on the line 6-6 of Fig. 4;

Fig. 7 is a sectional elevational view of a 80 modified form of motor;

Fig. 8 is a section on the line 8-8 of Fig. 7;

Fig. 9 is an elevational view partly in section of a still further modified form of my 85 invention;

Fig. 10 is a section on the line 10-10 of Fig. 9;

Fig. 11 is a part sectional elevational view of a still further modified form of driving 90 motor;

Fig. 12 is a section on the line 12-12 of Fig. 11;

Fig. 13 is a section on the line 13-13 of Fig. 12;

Fig. 14 is a plan view of the top of the operating lever of Fig. 11;

Fig. 15 is an elevational view of a further modified form of pawl and ratchet mechanism;

Figs. 16 and 17 are, respectively, plan and elevational views of further embodiments of my invention;

Fig. 18 is a sectional elevational view of a still further modified form of drive motor;

Fig. 19 is a section on the line 19-19 of Fig. 18; and

Fig. 20 is a section on the line 20-20 of Fig. 18.

Referring to the drawings in detail and first of all to the embodiment of my invention as illustrated in Figs. 1 to 6, inclusive:

In this embodiment of my invention I provide two hulls, shells or pontoons designated 1 and 2, respectively. These pontoons as 115 will be seen for instance from Fig. 3 are hollow and air-tight. They may be constructed of wood, metal or other suitable material.

In any event they are disposed in spaced apart relation to provide for the reception 120 of a structure designated 3 and which for purposes of description I shall call a cockpit, this cockpit in this embodiment of the invention mounting the motor mechanism, steering mechanism, propeller, etc. as well

as accommodating the operator's seat and providing space for the carriage of passengers or other cargo, as may be desired. This cockpit is secured to straps 4 which extend across the space between the pontoons 1 and 130

2 and are bent upwardly over the tops of the pontoons and then down the outer side. The straps are removably secured to the pontoons by wing nuts 5 and likewise the cockpit is removably secured to the straps by similar nuts 6. It will be seen, therefore, that the pontoons and cockpit may be taken down very readily for purposes of transportation and are quickly removable without the use 10 of any special tools and without the necessity of any particular skill.

In the bottom of the cockpit I mount a 15 slideable operator's seat 7, the seat being slideable fore and aft of the cockpit and being mounted on rollers 8 for this purpose.

As above stated the cockpit mounts the propeller and the propeller shaft. In this connection 9 designates the propeller shaft and 10 the propeller carried at the outer end 20 thereof. The propeller shaft adjacent its outer end rests upon a member 11 while its inner end is supported by a pivoted torque arm 12. This torque arm is pivoted at 13, the lower position of the propeller being 25 regulated by engagement of a lug on the torque arm with adjusting screw 14. This mounting of the propeller shaft, as will appear hereinafter, is to permit of the propeller lifting should the same strike an obstruction 30 while the boat is in use.

Forward of the operator's seat 7 and mounted within the cockpit 3 is the manually operated motor provided for driving the propeller. This motor may take different 35 forms, several of which have been shown in the accompanying drawings. The motor of the figures above referred to, that is, Figs. 1 to 6, inclusive, comprises a housing designated generally as 15 for the various gears, 40 pinions, etc. making up the motor. Extending through this housing and in line with the propeller shaft 9 is a main drive shaft 16. The forward end of this drive shaft projects through the housing and is provided with a 45 flywheel 17 frictionally held to the shaft through the medium of a spring 18. The rear end of the drive shaft 16 projects through the rear wall of the housing 15 and carries one member 19 of the special coupling 50 above referred to, the other member 20 of this coupling being carried by the inner end of the propeller shaft 9. The parting line of the coupling, that is, the line of part between the two members 19 and 20 is 55 directly in line with the pivot 13 of the torque arm 12 for a purpose which will be referred to later.

As above mentioned, the coupling is of special construction and by referring to Fig. 4 it will be seen that the adjacent faces of the coupling members 19 and 20 are provided with jaws 19' and 20'. With the propeller shaft 9 rotating in a forward direction the thrust of the propeller will maintain these 60 jaws in engagement. However, should the

propeller strike an obstruction then the jaws can separate permitting the propeller to be swung upwardly about the pivot 13. When the propeller shaft rotates in reverse direction the thrust of the propeller is in a direction tending to separate the jaws of the coupling, but such separation is prevented by undercutting the jaws as will be seen from the drawings.

On the drive shaft 16 and within the housing 15 are two bevelled pinions 21 and 22 which are in constant mesh with a bevel gear 23, the latter being mounted on a shaft 24 within the housing 15 and which shaft extends transversely of the drive shaft 16. The two pinions 21 and 22 are free on the drive shaft and in order that these pinions may be coupled or clutched to the drive shaft I provide clutch mechanism shown in some detail in Fig. 4a and comprising a sleeve 25 which is held on the shaft 16 against rotation but is slideable relatively thereto, this sleeve carrying cam mechanism shown at 26 and 27, each of these cams being engageable with the inner ends of two arms 28 and 29. These arms are pivoted at 30 and intermediate this pivot and the cam are provided with raised portion 31. The arms extend into an expandable ring 32 within the pinions. Consequently when the sleeve 25 is moved either to the left or right, as the case may be, the arms 28 and 29 will be forced apart to expand the ring 32 and frictionally clutch the pinion to the sleeve 25, and this sleeve being fixed to the drive shaft 16 the pinion will be held against rotation with respect to the drive shaft.

It will be apparent of course that inasmuch as the pinions 21 and 22 are on opposite sides of the gear 23 the pinions 21 and 22 will be rotated in opposite directions. This, therefore, provides for reversal of the direction of rotation of the propeller shaft 9.

The drive shaft 16 also carries a gear 33 in addition to the bevel gear 23 and this gear 33 meshes with a gear 34 carried on a shaft 35 lying above the shaft 34. The shaft 35 also carries a driving pinion 36 which is adapted to be driven by a rack 37. This rack 37 constitutes the manual means for driving the motor mechanism. The rack is provided with an extension 38 which is pivoted at 39 to a sleeve 40 mounted for sliding on a rod 41 lying beneath the rack. The sleeve 40 is provided with an upwardly extending portion 42 to which it attached one end of a coil spring 43, the other end of which is attached to the upper side of the rack as shown at 44. The purpose of this spring 43 is to tend to lift the rack 37 out of engagement with the pinion 36. For operating the rack the same is provided with a handle 45.

Extending through the bottom of the cockpit 3 is a rudder post 46 carrying at its

upper end a pinion 47 and at its lower end a rudder 48.

49 designates a rack which may be integral, for example, with a rudder bar 50 pivoted at 5 51.

The rack 37 and the rudder bar 50 are both so located with respect to the operator's sliding seat 7 as to be within easy and natural reach of the operator.

10 In operation the operator upon the seat 7 and with the seat in the position shown in Fig. 4, for instance, grasps the handle 45, places his feet upon each end of the rudder bar 50 and then by moving aft and pulling 15 with the arms draws the rack 37 across the top of and in engagement with the driving pinion 36. It is to be noted that the rack 37 is in such position with respect to the operator's seat that the rack is pulled substantially 20 horizontally on its working stroke. The rotation of the pinion 36 of course imparts rotation to the propeller shaft 9 through the gears 34, 33 and one of the pinions 21 or 22, the pinion coupled to the driving shaft 16 25 at the moment depending upon the direction in which it is desired to drive the boat. Upon the completion of the working stroke the operator slides forward to his original position again, at the same time raising the rack 30 37 out of engagement with the pinion 36. Thus, it will be apparent, that the operator moves on his idle stroke and returns to his original position practically without effort. In order that the motion of the propeller 35 shaft will continue during this idle stroke of the rack 37 the flywheel 17 above mentioned has been provided. As a consequence of this construction the propeller 10 will be rotated at a sufficiently constant speed to cause 40 the boat to travel through the water at a substantially uniform speed.

In the event that the propeller should strike an obstruction of any kind while the boat is traveling the outer end of the propeller shaft 9 is free to rise by reason of the 45 torque arm 12, the latter pivoting about its pivot 13 and inasmuch as this pivot is in line with the division or parting line of the coupling members 19 and 20, this lifting of the propeller shaft is permitted and the shaft will be disconnected or uncoupled from the driving shaft 16, thereby preventing injury to the propeller. After the obstruction has 50 been passed the propeller shaft will simply fall to its original position and be coupled automatically again to the drive shaft 16.

In the event that it is desired to reverse the direction of travel of the boat, the reversing lever 52 is operated to shift the sleeve 25 in 60 the desired direction to effect its reversal, this shifting of the sleeve as above explained disconnecting one of the pinions 21 or 22 from the drive shaft 16 and connecting the other one to this shaft.

65 In the embodiment of my invention illus-

trated in Figs. 7 and 8 I have shown a modified form of motor adapted for incorporation in my improved construction, the motor however still being constructed to drive a propeller mounted aft as in the form or embodiment of the invention so far described. In this form of my invention 53 designates a short shaft mounted in bearings in the motor housing 54, the rear end of this shaft 70 projecting through the housing and carrying one member 55 of a coupling, this member 75 cooperating with a coupling member 56 which is carried on the forward end of the propeller shaft 9'. This shaft, as before, is mounted or rather its forward end is mounted 80 in a torque arm 12' pivoted at 13' and having its downward movement limited by a stop screw 14'.

The inner or forward end of the short shaft 53 carries a bevel gear 57 which is fast on the shaft and in constant mesh with two opposed bevel gears 58 and 59. The last two gears are mounted freely on a drive shaft 60, this shaft extending vertically substantially as distinguished from the longitudinal extension of the shaft 53 and propeller shaft 9'.

85 Fast on the drive shaft 60 is a clutch sleeve 61 which may be of any suitable construction and is adapted to be moved in both directions longitudinally of the shaft 60 so as to clutch or couple the gear 58 or the gear 59, as the case may be, to the shaft 60. The lower end of the drive shaft projects through the bottom of the motor housing 54 and is provided 90 with a flywheel 62.

The drive shaft is mounted in suitable bearings 63 and 64 and above the upper bearings 64 and fast to the shaft is a gear 65 which I will term a drive gear, this gear meshing with a large gear 66. This latter gear is rotated manually always in the same direction, anticlockwise as viewed in Fig. 7. The gear 66 is mounted on a shaft 67 and on this same shaft is a rotary disc 68, this disc or rotor lying within the gear 66 which is formed with a depression in its face to receive the disc.

100 The disc or rotor 68 is provided at intervals with notches 69 which are of such shape as to provide a wedge-shaped space between the periphery of the disc or rotor and the inside of the gear 66. In each one of these wedge-shaped spaces is a ball 70 backed by a 105 spring 71.

110 Secured to the rotor 68 in any suitable fashion is an operating lever 72. This lever, it will be understood, is to be operated from an operator's seat such as the seat 7 of the 115 form of my invention already described, and the wedge-shaped spaces above referred to between the rotor 68 and the inner face of the gear 66 are so shaped that when the lever 72 is pulled to the left, as viewed in Fig. 7, the 120 balls 70 will wedge in these spaces thereby 125 130

effecting a drive from the rotor to the gear 66. Rotation of the gear 66 in an anti-clockwise direction will, of course, impart rotary motion to the shaft 60 and through the gear 58 or 59, as the case may be, and gear 57 together with coupling members 55 and 56 impart rotation to the propeller shaft 9'.

It will be noted that by providing the wedge-shaped spaces between the rotor 68 and the gear 66 that movement of the lever 72 to the right or clockwise, as viewed in Fig. 7, disconnects the rotor from the gear so that the return of the lever 72 through its idle stroke and to its original position ready for the next stroke may be effected without any effort on the part of the operator.

74 designates a reversing lever, this reversing lever being fixed to the arm 75 of the clutch mechanism 61, the two being pivoted on a fixed pivot 76. This lever 74 is provided with a cam 77 which is adapted to cooperate with a pin 78. When the reversing lever is in reverse position it will be moved downwardly from the position shown in Fig. 7 and this movement of the lever will pull the cam 77 downwardly to move the pin 78 against the action of spring 79 into a hole 80 in the extension 73 of the torque arm, thereby holding the torque arm against any pivotal motion.

It will be understood that on the forward motion of the boat the action of the propeller is in a direction to pivot the torque arm 12' in an anti-clockwise direction, as viewed in Fig. 7, and such motion is limited by the stop screw 14'.

In the embodiment of my invention as shown in Figs. 9 and 10, I provide a drive shaft 81 mounted in suitable bearings and carrying two pinions 83 and 84 loose on the shaft and a clutch sleeve 85 non-rotatable on the shaft but slideable longitudinally thereof, the ends of this sleeve being provided with jaws engaging jaws in the hub of the pinions 83 and 84. The rearward end of the drive shaft 81 is provided with a flywheel 86 and 87 designates a coupling adapted to couple the drive shaft 82 to the propeller shaft 9'.

The bevel pinions 83 and 84 are in constant mesh with a bevel gear 88 on a shaft 89 extending at right angles to the drive shaft 82 and this same shaft 89 carries keyed to it a disc or rotor 90 provided in its periphery with notches 91 similar to the notches in the periphery of the rotor 68 of the embodiment of my invention shown in Fig. 7.

Loosely mounted on the shaft 89 is a drum 92 carrying in one face a spring 93, one end of which is anchored to the drum at 94 and the other end to the motor housing as shown at 95, for instance. This drum, as will be seen particularly from Fig. 10, is cut back in one face so as to accommodate the rotor 90 and in the space provided between the

periphery of the rotor 90 and the spring drum 92 by the notches 91 I provide rollers 96.

The periphery of the drum 92 is provided with an operating strap 97 provided with a suitable handle 98 for manipulation of the strap. The handle 98 is within convenient reach of the operator's seat such as the seat 7 of Fig. 4 and when the strap 97 is drawn to the left, as shown in Fig. 9, to rotate the spring drum 92 against the action of the spring 93, the rollers 96 will wedge between the drum and the rotor 90 so that motion in the same direction will be imparted to this rotor and hence to the shaft 89. This will effect a drive of the bevel gear 88 and of either the pinion 83 or 84, depending upon which one of these pinions is clutched to the drive shaft 81 at the moment, to drive the propeller shaft 9' in a corresponding direction. The reversing lever for the clutch mechanism 85 is designated 99.

In this embodiment of my invention I have shown the rudder bar at 50° and a rack 49°, pinion 47° and rudder 48° in the same position relatively to the motor as in the embodiment of my invention shown in Fig. 4.

In the form of my invention as illustrated in Figs. 11 to 14, inclusive, the drive shaft is designated 100 and as in the other forms of my invention is provided with a coupling member 101 which, as will be understood, cooperates with a similar coupling member on the propeller shaft. The other end of the shaft 100 carries a flywheel 102.

Extending transversely of the motor housing is a shaft 103 mounted in suitable bearings 104, this shaft carrying at one end a gear 105 keyed to the shaft. This gear meshes with a pinion gear 106 on a shaft 107 which is mounted in suitable bearings 108 in the motor housing. This shaft 107 carries a spur gear 109 at one end meshing with a gear 110 fast on the shaft 100.

The shaft 103 has also keyed to it a ratchet wheel 111. Loose on the shaft 103 and intermediate the ratchet 111 and gear 104 is a lever 112.

A spring 113 resists rotation of the lever on its shaft.

As will be seen from Fig. 12 the lever 112 is provided with a cup-shaped or sleeve-shaped formation 114 adjacent its upper end and this formation is in turn provided with a depression 115 for an adjustable member 116 which is carried on the lower end of a reversing rod 117. The rod 117 extends through a sleeve 118 which in turn is mounted in a sleeve 119 supported by pivot pins 120 which are mounted in the cup-shaped formation 114.

Meshing with the ratchet 111 is a pawl 121 which as will be seen from Fig. 12 is bent laterally to provide a portion 122 which is secured to the sleeve 119 by screws 123. The

sleeve 119 has a slight rocking motion which is controlled by the stop 116 and upon an inspection of Figs. 11 and 12 it will be seen that with the stop 116 in the position shown 5 in the drawings the lever 117 is movable to engage the pawl 121 with the ratchet 111 to drive the latter anti-clockwise, as viewed in Fig. 11, for instance, the pawl moving out of engagement with the ratchet 111 on the 10 reverse stroke of the lever, this latter motion of the pawl is limited by the stop 116 to prevent the other end of the pawl from engaging the ratchet.

We can assume that this is for forward 15 motion of the boat.

When it is desired to reverse, the member 124 on the upper end of the rod 117 is given a partial turn and the stop 116 engaging the depression 115 will effect a rocking of the 20 pawl 121 so that the pawl then will be thrown out of engagement entirely with the ratchet 111 for movement of the lever 117 to the left, the other end of the pawl however on movement to the right of the lever engaging 25 the ratchet to drive the ratchet clockwise.

In Fig. 15 I have modified this construction somewhat, the pawl 121' which is mounted on the lower end of rod 117' being given a 180° turn when it is desired to reverse.

30 A spring pressed ball 125 is adapted to engage the depression in the rod 117' to hold the rod in its adjusted position so far as the seating of the pawl is concerned.

In the embodiment of my invention as illustrated in Figs. 16 to 20, inclusive, I have shown a modification which is particularly well adapted for a rigid drive from the motor to the propeller as distinguished from the other embodiments of my invention above 35 described wherein I provide a coupling between the drive shaft and the propeller shaft, although it is to be understood that the motor of this embodiment of my invention is adapted also for use with a coupling drive if 40 desired.

In these figures it will be seen also that I have illustrated a boat having a hull similar to a conventional boat as distinguished from the pontoon or shell form of Figs. 1 and 2. 50 The hull of the boat is designated 126 and the motor shewn in detail in Fig. 18 is designated 127. The propeller shaft is designated 128 and extends from the bottom of the motor, aft to the rear of the boat where it is 55 provided with a propeller 129.

The motor 127 comprises a rotor 130 fast on a shaft 131. This rotor is similar to the rotor 90 of Fig. 9 and is provided in its periphery with notches 132. The rotor 130 is 60 received by a gear 133. In the space provided by the notches 132 and lying intermediate the rotor and the gear are rollers 134, these rollers being provided for the purpose of causing a wedging action between 65 the gear 133 and the rotor 130 when the for-

mer is rotated anti-clockwise as viewed in Fig. 18.

To impart rotation to the gear 133 I provide a rack 135 which rack is provided with teeth encircling the same and at its outer end with a handle 136 so that the rack may be reciprocated as will be understood.

The shaft 131 also carries a bevel gear 137 which is fixed to the shaft and is in constant mesh with a bevel pinion 138 carried on the end of a shaft 139 which extends substantially vertically of the motor structure and is mounted in suitable bearings 140. This shaft 139 is provided at its lower end with a flywheel 141 and is coupled through coupling 142 with another shaft 143 below it. The lower end of this shaft 143 is provided with a bevel pinion 144 and this pinion is adapted to mesh with either of two pinions 145 and 146. These two pinions are mounted on the propeller shaft 128 and are adapted to be shifted by a shift arm 147 to bring either the pinion 145 or pinion 146, as the case may be, into engagement with pinion 144. Inasmuch as the pinions 145 and 146 are on opposite sides of the pinion 144 it will be appreciated that this provides for reversal of the direction of drive of the propeller shaft 128.

55 The handle 136 of the operating rack 135 is, as will be seen from Fig. 16, within easy reach of an operator on the sliding seat 7. In this embodiment of my invention I have mounted the rudder designated 148 at the rear of the boat and this rudder is operated by a rudder bar 149, each end of which is connected to the rudder 148 by cables 150.

100 It will be appreciated that in this form of my invention on the idle stroke of the rack 135 the rack remains in engagement with the gear 133 so that the direction of this gear is reversed but owing to the shape of the notches provided in the rotor 130 it will be appreciated that the driving connection between this gear and the rotor is not established on this movement of the gear so that the operator may return to his original position ready for the next working stroke practically without effort.

105 In all the forms of my invention above described it will be appreciated that I have provided for the application of power to the manually driven motor in a most efficient manner. In those forms of my invention such as illustrated in Figs. 4, 9 and 13 it will be further appreciated that the motor operating member moves in a straight line on its operating stroke. This permits the operator to apply his full power to the motor throughout his entire working stroke.

110 It will be appreciated also that in the forms of my invention illustrated in Figs. 4, 7, 9 and 10 the operating member whether the same be a lever, a strap or a rack is disengaged from the motor on the idle stroke 115

of the operator so as to permit him to return to position for the next working stroke with the minimum of effort on his part.

It will be further appreciated that in all the forms of my invention I have provided a flywheel the inertia of which maintains the propeller in motion while the operator is returning from the end of a working stroke to the beginning of a new stroke, or in other words is moving on an idle stroke. This insures that the boat will move through the water at a substantially constant speed.

It will be further appreciated that in all the forms of my invention above described I have reduced the parts required particularly in the construction of the motor to the minimum, thereby insuring that the boat may be manufactured and sold to the consumer on a commercial basis, the design, however, being such as above pointed out as to insure maximum efficiency and long wear.

What I claim is:—

1. In a boat the combination of a propeller, a motor for driving the same and including a main drive gear, a rack for driving said gear, and a slideable operator's seat from which said rack is reciprocated.

2. In a boat the combination of a propeller, a motor for driving the same, an operator's seat and a pivoted rack manually operable from said seat for driving said motor.

3. In a boat the combination of a propeller, a motor for driving the same, an operator's seat, a rack operable from said seat for driving said motor, a pivot for said rack, said motor comprising a main drive gear, said rack engaging said gear on its working stroke and pivoting out of engagement with said gear on the reverse or idle stroke.

4. In a boat the combination of a propeller, a motor for driving the same, manually operable means for driving said motor, a sliding seat from which to operate said manually operable means, said means comprising a slideable pivotally mounted rack, said motor comprising a gear engaged by said rack on movement of the rack and seat away from the motor, said rack pivoting out of engagement with said gear on the reverse movement of the rack and seat.

5. In a boat the combination of a propeller, a propeller shaft, a drive shaft, a separable coupling between the propeller and drive shaft, a pivoted torque arm for the propeller shaft arranged with respect to the coupling whereby on pivoting of the torque arm to lift the propeller said coupling will be separated to disconnect the propeller shaft and drive shaft, the coupling being provided with cooperating jaws so arranged that upon movement of the propeller to drive the boat rearwardly separation of said coupling members is prevented.

6. In a boat the combination of a propeller, a propeller shaft, a drive shaft, a two-part

coupling coupling the propeller shaft to the drive shaft, the two parts of said coupling being provided on their adjacent faces with cooperating jaws, said coupling being so disposed with reference to the propeller that on movement of the propeller to drive the boat forward the two members of the coupling will be maintained in engagement with each other, the jaws of said coupling being undercut whereby on reverse movement of the propeller separation of the coupling members is prevented.

7. In a boat the combination of a propeller shaft, a motor for driving the same, said motor comprising a rotor, a gear, a slip clutch between said gear and rotor, a rack for rotating said gear in reverse directions, said clutch maintaining said rotor and gear connected on one direction of rotation of the gear by said rack and permitting said gear to rotate in the opposite direction without imparting rotation to said rotor, and reversing mechanism intermediate the motor and propeller shaft.

8. In a boat the combination of a propeller shaft, a motor for driving the same, said motor comprising a drive shaft, reversing mechanism between said drive shaft and propeller shaft, a rotor, a shaft carrying said rotor, a gear on said shaft, a pinion on the drive shaft in mesh with said gear, a second gear, a slip clutch between said second gear and rotor, a rack for operating said second gear, movement of the rack in one direction to drive said second gear driving said rotor and drive shaft through said clutch, said clutch permitting rotation of said second gear in the opposite direction without imparting motion to said rotor.

9. In a boat the combination of a propeller shaft, a drive shaft, reversing mechanism intermediate the two shafts, a flywheel carried by said drive shaft, a pinion on said drive shaft, a gear in constant mesh with said pinion, driving means for said gear, and a slip clutch intermediate said driving mechanism and said gear whereby the driving mechanism will effect on one motion only rotation of said gear.

10. In a boat the combination of a propeller shaft, a motor for driving the same and comprising a rotor, a gear, a slip clutch between said gear and rotor, a rack for rotating said gear in reverse directions, said clutch maintaining said rotor and gear connected on one direction of rotation of the gear by said rack and permitting said gear to rotate in the opposite direction without imparting rotation to said rotor, and a slideable operator's seat from which said rack is reciprocated.

11. In a boat the combination of a propeller shaft, a motor for driving the same and comprising a rotor, a gear, a slip clutch between said gear and rotor, a rack for rotating

said gear in reverse directions, said clutch maintaining said rotor and gear connected on one direction of rotation of the gear by said rack and permitting said gear to rotate in the opposite direction without imparting rotation to said rotor, a fly wheel rotatable with the propeller shaft, and a slidable operator's seat from which said rack is reciprocated.

This specification signed this 12th day of
10 December, 1930.

LEON N. HAMPTON.
